(57) **CLAIM**

The ornamental design for a door and window sensor, as shown and described.

DESCRIPTION

FIG. 1 is a perspective view of a door and window sensor; FIG. 2 is a top view of the door and window sensor of FIG. 1;

FIG. 3 is a bottom view of the door and window sensor of FIG. 1;

FIG. 4 is a front view of the door and window sensor of FIG. 1;

FIG. 5 is a rear view of the door and window sensor of FIG. 1;

FIG. 6 is a left side view of the door and window sensor of FIG. 1; and,

FIG. 7 is a right side view of the door and window sensor of FIG. 1.

1 Claim, 4 Drawing Sheets
